(57) **CLAIM**

(**) Term: **14 Years**

The ornamental design for a handheld biomedical monitoring device, as shown and described.

(21) Appl. No.: **29/203,950**

DESCRIPTION

(22) Filed: **Apr. 21, 2004**

FIG. 1 is a front elevational view of the handheld biomedical monitoring device, showing a new ornamental design thereof;

(51) LOC (8) Cl. **24-01**

FIG. 2 is a rear elevational view thereof;

(52) U.S. Cl. **D24/186**; D10/81; D10/78

FIG. 3 is a first side elevational view thereof;

(58) Field of Classification Search D10/78,

FIG. 4 is a second side elevational view thereof;

D10/81; D24/107, 186; 600/301, 495, 592,
600/587, 595

FIG. 5 is a top plan view thereof; and,

See application file for complete search history.

FIG. 6 is a bottom plan view thereof.
